VISE-JAW-RELEASING MECHANISM

Lester Gowing, Nanaimo, British Columbia, Canada

Application September 28, 1953, Serial No. 382,793

2 Claims. (Cl. 81—36)

This invention relates generally to vises, and in particular to woodworkers' vises, which may be tilted at any angle to the work bench to facilitate the holding of materials in advantageous position, and to provide a sturdy implement which is also simple, and economical to manufacture.

An object of this invention is to provide a vise having a hinged plate for angular attachment to a work bench.

Another object of this invention is the provision of a vise having tiltable jaws, and in which the movable jaw can be adjusted by the regular screw, or can be released, and slid bodily in or out relatively to the rear jaw by means of a split-nut mechanism.

Still another object of the invention is the provision of novel releasing means for the split nut, to enable the movable jaw to slide freely.

The foregoing and other objects and advantages will appear more fully hereinafter from a consideration of the detailed description which follows, taken together with the accompanying drawings as illustrated by way of example, in which:

Figure 1 is a vertical longitudinal sectional view of the preferred embodiment of the vise.

Figure 2 is a horizontal sectional view of the vise.

Figure 3 is a vertical, longitudinal sectional view of the vise similar to Fig. 1, but shows the split-nut release mechanism in nonoperative position.

Figure 4 is an elevation of the outer face of the movable jaw.

Figure 5 is a side elevation of the vise positioned vertically, the jaws being disposed parallel to the top of the work bench.

Figure 6 is a side elevation similar to Fig. 5 but showing the vise jaws disposed at right angles to the top of the work bench, and

Figure 7 is a transverse vertical sectional view taken on the line 7—7 of Fig. 6, showing the rear jaw in elevation and showing the means for retaining the jaws in rotational engagement with the vise frame, but omitting the vise-supporting lugs and hinge plate.

Similar reference numerals designate corresponding parts in the various figures of the drawings.

Referring to Fig. 1, the preferred embodiment of the vise as illustrated comprises a frame 1, a supporting plate 2, adapted to be secured to a work bench 3, as shown in Figs. 5 and 6, said plate having a terminal ear 4 to which the vise frame is pivotally attached through the medium of a lug 5, and a pivot pin 6.

The frame 1 is tubular and is provided at one end with a circular flange 7 to which is rotatably attached a rear jaw member 8, held in place by semi-circular plates 9 secured to the jaw 8 adjacent its outer edge, the jaw thus being adapted to rotate on flange 7. The rear jaw 8 is formed with a boss 11, and is rotatably mounted in the tubular frame 1, the frame having a shoulder 12 to resist the end thrust of the jaw 8.

A movable jaw member 13 having spaced guide bars 14 extending from its inner face through a central opening

2

in the rear jaw, is slidably connected with the frame and the rear jaw member 8 by means of a bearing 38. An adjusting feed screw 15 extending axially of the tubular frame, is rotatably mounted in the jaws 8 and 13, said screw having a head 16 rigidly attached to its outer end by a pin 17, in which is positioned the usual slidable cross handle 18. The head 16 abuts against the outer face of the movable jaw 13, and both jaws 8 and 13 are provided with reinforcing ribs 19 and 20, respectively. At the end of frame 1, remote from the jaws, the screw 15 engages a split nut 21 having the same gauge threads as those of the screw to actuate the movable jaw, and at the same time acting as a second bearing for the screw. As will be seen from the drawing in Fig. 1, the split nut 21 is slidably contained in an annulus 22, which is provided with rearwardly divergent, opposite inner walls or surfaces 23, on which outer forwardly convergent walls or surfaces of the split nut slide, the split nut being in two sections and the sections having a wedge-shaped configuration corresponding with that formed by the opposite inner walls of the annulus 22.

The annulus 22 is rotatably secured in the tubular frame 1 by means of set screws 24 engaging a groove 25 in the annulus, the latter bearing on a shoulder 26 in frame 1.

To release the split nut from engagement with the screw 15, a release frame is provided, said frame comprising a sleeve element having a flange 27 having openings through which the guide bars 14 extend, and a boss 28 surrounding the screw for engaging the split nut upon sliding movement of the release frame. A handle 29 is secured to the flange of the release frame for manual actuation to release the split nut 21, and adjacent the opposite end of the nut, a keeper 30 surrounds screw 15 and is slidably mounted on guide bars 14 to prevent the parts of the split nut from falling out of place when disengaged from the screw 15. The sleeve element and the keeper are connected to move in unison by means of bars 31, which are positioned adjacent to, and slide on the guide bars 14, as clearly illustrated in Fig. 2. In Fig. 3 the construction of the split nut in the released position is clearly illustrated, and needs no further description.

There is a cutaway portion 32 in the frame 1 to enable the operator to grasp the handle 29. In Figs. 5 and 6, the pivoting arrangements are shown. In Fig. 5, the jaws are disposed parallel to the top of the work bench 3, while in Fig. 6, the jaws are disposed at right angles to the top of the work bench, dotted lines showing the position of the jaws after they have been rotated around the axis of the tubular frame, through an angle of 90°.

In the construction of the pivoting arrangement, it will be seen that the supporting plate 2 is secured to the work bench 3 by counter-sunk set screws 33, or the equivalent, and the frame 1 is hinged to the plate 2, through the medium of the pivot pin 6. A bracket 34 is secured to the under side of the work bench 3, and a slotted bar 35 is pivoted thereto. A threaded pin 36 is attached to the frame 1, and is adapted to slide in the slot of bar 35. The pin 36 is engaged by a clamping handle 37, so that the vise may be clamped in any position of angular adjustment, and since the jaws can also rotate on the frame, a virtual universal adjustment of the vise may be obtained.

Often it is necessary to hold articles that are tapered transversely to the jaw members, and in order to provide proper bearings for such articles the movable jaw 13 is pivotally mounted on the end of bearing 38 by means of pins 39. The opposite sides of the bearing are rounded as at 40, in Fig. 2 to permit pivotal movement of the jaw 13. To secure the jaw 13 against pivotal movement pins 41 are carried by the jaw which engage in grooves 42 formed in the bearing, which pins are removable.

From the foregoing it will be seen that I have pro-

vided a vise which is very easy to manipulate, is capable of wide variations of adjustment, and is both simple and economical to manufacture.

It is believed that the construction and advantages of the structure shown may be apparent from the foregoing paragraphs taken in conjunction with the accompanying drawings without further detailed description.

While the preferred embodiment of the invention has been disclosed it is understood that minor changes in the construction, combination and arrangement of co-operating parts may be resorted to within the scope of what is claimed without departing from the function of the invention.

I claim:

1. In a vise; a tubular frame; an inner jaw rotatably mounted on one end of said frame; a feed screw extending axially of said frame and slidably mounted through said inner jaw; an outer jaw mounted on the end of said feed screw and movable towards and from said inner jaw; guide bars extending from said outer jaw longitudinally of said frame on opposite sides of said feed screw, an annulus rotatably mounted in the opposite end of said frame and having opposite divergently beveled inner walls, a split nut having sections threaded on said feed screw, said sections having opposite convergently beveled outer faces adapted to seat upon the beveled inner walls of said annulus, and means surrounding said feed screw and slidably mounted on said guide bars for contact with said split nut to move the nut outwardly from said annulus to release the nut sections from engagement with said feed screw.

2. In a vise; a tubular frame, an inner jaw mounted on one end of said frame, a feed screw extending axially of said frame and slidably mounted through said inner jaw, an outer jaw mounted on the end of said feed screw and movable towards and from said inner jaw, guide bars extending from said outer jaw longitudinally of said frame on opposite sides of said feed screw, an annulus mounted in the opposite end of said frame and having opposite divergently beveled inner walls, a split nut having sections threaded on said feed screw, said sections having opposite convergently beveled outer faces normally seated upon the beveled inner walls of said annulus, a collar surrounding said feed screw at one end of said split nut and slidably mounted on said guide bars for moving said nut outwardly from said annulus to release the nut sections from engagement with said feed screw, and a keeper surrounding said feed screw on an opposite end of the split nut and connected to said collar for movement in unison therewith.
